UNITED STATES PATENT OFFICE.

EDOUARD DE VLIEGER, OF BRUSSELS, BELGIUM.

AUTOMATIC COUPLING.

No. 884,801.

Specification of Letters Patent.

Patented April 14, 1908.

Application filed June 27, 1907. Serial No. 381,174.

To all whom it may concern:

Be it known that I, EDOUARD DE VLIEGER, a subject of the King of the Belgians, residing at Brussels, in the Kingdom of Belgium, have invented certain new and useful Improvements in Automatic Couplings, and do hereby declare the following to be a full, clear, and exact description of the invention, such as will enable others skilled in the art to which it appertains to make and use the same.

The present invention relates to improvements in automatic couplings and refers specially to the De Vlieger coupling system (British Patent No. 2612 2nd February 1904) with split cup and pivoted coupling hook designed to engage behind a bolt forming the end of the cup.

The improvements have as their particular object to make the coupling reversible, to simplify the construction and to make it stronger, to increase the security of action and engagement and to enable the uncoupling to be effected from either side of the car. These improvements are shown in the annexed drawings, in which

Figure 1 is a view in plan of the reversible coupling in the coupled position. Fig. 2 is a side view. Fig. 3 is a side view showing in detail the hook engaged in the cup. Fig. 4 is a front view of the cup showing the slot and the bolt. Fig. 5 is a transverse section on a smaller scale of the cup, bolt and hook and of the new arrangement for controlling the bolt by a counterweight lever. Fig. 6 is a side view of the cup with the control lever of the bolt.

The improved coupling consists of:

1st. A coupling piece B jointed to one of the ends of the coupling bar C, to which it is fixed by a vertical pin A. It can be displaced angularly about this pin as an axis in order to follow the movements of the carriages on curves of short radius (75 meter) (83 yards). At one of its ends there is an inclined spout D designed to receive the coupling hook E and to keep it in a position parallel to the road when this hook is left to itself. This spout has an enlarged receiving opening (d) to permit a certain horizontal deviation of the hook and the coupling on curves. At the other end of the coupling piece is the cup F. The central part is provided with a supplementary hook H comprising a coupling stirrup corresponding in dimensions with the stirrups of all the inter-

national continental systems, which permits of coupling with wagons not yet provided with the automatic coupling.

2nd. Of the above mentioned cup F forming an inclined plane. This cup is intended to receive the coupling hook E of another carriage; it is jointed about a horizontal pin G so that it may be raised when it is desired to do any shunting without coupling, or to make coupling with carriages not provided with the automatic coupling. A longitudinal groove or slot (f) runs along the whole length of the inclined plane of the cup, this groove enables the hook, at the moment of uncoupling, to pass under the cup when the bolt is unfastened which keeps it coupled. These cups are provided with turned over edges for preventing the hooks from jerking out when the carriages jolt.

3rd. Of a movable bolt I. This bolt is provided with a notch (i) into which fits an elbow lever (i') jointed at the upper end. The lower end of this lever is provided with a counterweight (i²) placed well outside the vertical plane through its point of attachment. This arrangement combined with the form of the notch (i) insures the constant and automatic closing of the bolt.

4th. Of a coupling hook E provided with two shoulders designed to guide it into the cup F and serving at the same time as large sliding surfaces between the hook and the inclined plane of the cup. The hook may be raised to facilitate shunting, but in order that it may not lift of its own accord it is provided with a ring, on to which hooks the end of a short chain (e), the other end of which is fixed to the spout D. An inclined plane (f²) situated behind the cup F automatically lifts the hook (when coupling) to prevent it striking against the framing in rough shunting, which insures due coupling even if one supposes the carriages to be sent forward at a speed of 12-13 miles.

The whole arrangement of coupling piece, with cup, hook etc. is duplicated on each carriage, which insures a double security and which constitutes the reversibility of the apparatus.

Uncoupling can be effected from either side of the road owing to the following arrangement: A double horizontal lever L is situated on a vertical pin rigid with the cup F, one of its extremities is connected to the vertical lever (i) by two chain links, (l) the other end of this small lever is connected to a

rod or to a chain L' having a handle or hand-hold L^2 projecting to the other side of the carriage. To uncouple, all that is necessary is to pull on the lever L by the handle L^2 attached to the small chain, another handle L^3 being placed at the opposite end of the chain so as to afford a man an opportunity to pull back the lever L to force in the bolt I . In the case of shunting without coupling it is sufficient to fix this chain to a hook fitted for this purpose; the bolt remaining open there is no coupling; this also avoids raising the cups.

The cups F and the hooks E being lowered, the carriages are pushed one against the other, the hooks E meeting the inclined planes of the cups are raised until the moment when, leaving the inclined planes, they fall on the coupling bolts I ; at this moment the coupling is effected. To uncouple, it is sufficient after having loosened the coupling, to raise the counterweight lever (i') by pushing the lever L or by pulling the chain L' by the handle L^2 operating the lever, L of the other side, at the same time the bolts I are thus simultaneously withdrawn and the hooks E fall through the slots (f). When the lever (i') and the chain are released, the bolts I close and the coupling is ready for use again.

Having now described my invention what I claim and desire to secure by Letters Patent is:—

1. In combination in an automatic reversible coupling gear, a coupling bar pivoted upon the end of the traction rod so as to swing in a horizontal plane, a coupling cup fixed at the one side of the said bar and a coupling hook fixed at the other end of the bar by a horizontal pivot so as to allow the said hook to travel in a vertical plane.

2. In combination in an automatic reversible coupling gear, a coupling bar adapted to have a horizontal movement, a coupling cup fixed at one side of the said bar, a central slot 45 in the said cup, fixed inclines on either side of

the said slot, turned over edges to prevent the hook from jerking out, when the carriages jolt and a coupling hook fixed at the end of the bar, a horizontal pivot for attachment of the said hook permitting the said hook to travel in a vertical plane and a twisted end to the said hook to permit it to travel on the inclined faces of the coupling cup.

3. In combination in an automatic reversible coupling gear a coupling bar adapted to have a horizontal movement, a coupling cup fixed at one side of the bar, a coupling hook fixed at the other end of the bar by a horizontal pivot so as to allow the said hook to travel in a vertical plane, and a connecting chain between the pivot frame and the hook.

4. In combination in an automatic reversible coupling gear a coupling bar adapted to have a horizontal movement, a coupling cup fixed at one side of the said bar, a recess made where the end of the hook falls down to couple, hollows on either side of the said recess, to permit the hook to move horizontally and a coupling hook fixed by a horizontal pivot at the other end of the bar.

5. In combination in an automatic reversible coupling gear, a coupling bar adapted to have a horizontal movement, a coupling cup fixed at one side of the said bar, a slot running the whole length of the coupling cup, a coupling bolt fitting across the top part of the slot therein, a lever connected to the said bolt, loaded with a counter weight and the engagement of the lever in a slot in the said bolt, so that the lever is shot when the counter weighted lever is down, and drawn back when it is lifted; and a coupling hook upon the other end of the bar.

In testimony whereof I have affixed my signature in presence of two witnesses.

EDOUARD DE VLIEGER.
